UNITED STATES PATENT OFFICE.

ALMON E. NORRIS, OF BROOKLINE, MASSACHUSETTS.

CABLE-RAILWAY.

1,358,976.

Specification of Letters Patent. Patented Nov. 16, 1920.

Application filed April 1, 1918. Serial No. 225,862.

To all whom it may concern:

Be it known that I, ALMON E. NORRIS, a citizen of the United States, and a resident of Brookline, in the county of Norfolk and State of Massachusetts, have invented an Improvement in Cable-Railways, of which the following description, in connection with the accompanying drawings, is a specification, like characters on the drawings representing like parts.

This invention relates to cable railways, and more particularly to means for automatically releasing and applying the cable grip which is carried by the cable car.

15 The invention will be best understood by reference to the following description when taken in connection with the accompanying illustration of one specific embodiment thereof, while its scope will be more particularly pointed out in the appended claims.

In the drawings:—

Figure 1 is a side elevation showing a portion of the cable railway with the car approaching a position where its grip is about 25 to be released from the cable;

Fig. 2 is a similar view showing the position of the car at the point where the grip has again engaged the cable;

Fig. 3 is a plan view of the device located 30 at the side of the trackway for operating the cable grip;

Fig. 4 is a side elevation of the same with the parts in their normal position;

Fig. 5 is a similar view showing the grip-closing member elevated in response to an abnormal condition;

Fig. 6 is a rear end elevation of the cable car, cable grip and grip-controlling device; and

40 Fig. 7 is a plan view showing the arrangement of the cable in the vicinity of the cable-controlling device.

In the drawings, for illustrative purposes, I have shown one form of the invention as applied to a cable road having the trackway 1 on which there is adapted to travel one or more cars 2 provided with the cable-gripping device 3 adapted to be engaged with or disengaged from the driving cable 4.

50 While my invention as to many of its features may have wide and useful application in other connections and may be utilized in cable railways for other purposes than the specific one herein described, I have 55 here illustrated the same as providing means for automatically releasing the grip of each

cable car from the cable as the car reaches a certain point in the track,—as, for instance, the point where the cable is diverted from the track to the cable-driving mechanism,—and then automatically gripping the car to the cable at a point farther on where the cable again leads to the track from the driving mechanism. Cableway systems of this type are shown, for example, in prior 60 patents to J. M. McClellon Nos. 1,096,931 and 1,096,932 granted May 19, 1914.

Referring to the drawings, the cable portion 4 traveling in the direction of the arrow (Fig. 1) passes between the tracks 1 to 70 the sheave 5, thence down to the cable-driving mechanism (not shown). Returning, it passes over the sheave 6, over the smaller guide sheave 7, between the guards 8, and presents thereat to the cable grip on the car 75 the traveling cable portion 4'. As the car approaches the sheave 6, the cable grip 3 is caused to be released, the trackway being given a slight upward inclination thereat so as to lift the released grip clear of the 80 cable and clear of interference with the sheaves and adjoining cable portions. This lifting movement is further accentuated by a relatively abrupt depression in the trackway at 9, so that while the car is coasting 85 from the point of release to the point where the grip passes the sheave 5, and particularly while the forward trucks are traveling down the incline 9, the grip is held lifted above the point where it can interfere with 90 either of the two cable strands 4 and 4'. As the rear trucks pass down the incline 9, however, the two jaws of the grip are brought down on either side of the cable, being drawn into centering alignment there- 95 with by the guide plates 8, and the grip is thereupon again applied to the cable and the car continues its cable-drawn travel.

The cable grip may be of any suitable or desired construction, such, for illustration, 100 as that shown in my prior Patent No. 1,154,652 granted Sept. 28, 1915. Such grip, for example, may comprise the gripping jaws 3 adapted to engage the cable, and carried by the pivoted levers 10 and 11 adapted 105 to be moved to open and close the jaws by means of the toggle 12 operated by the upright link 13, the latter attached to a rocker arm 14 carried by the rock shaft 15, the gripping jaws and toggle, as in my afore- 110 said prior patent, being capable of a limited swinging movement transversely the car.

The grip may be manually applied and released when desired by means of the hand lever 16 secured to the rocker arm 14, but to provide means for automatically applying and releasing the same, the rocker shaft is prolonged at the side of the car and has secured thereto the lever arm 17 carrying the roll 18, which, at the appropriate time, is brought into engagement with grip-operating devices located at the side of the trackway.

The stationary grip-operating devices may be of any suitable construction, but herein they are so disposed that they act to release the grip as it approaches the sheave 6 and to apply the grip to the cable strand 4' after it has traveled past the sheave 5.

To this end, a suitable fixed supporting frame is provided at the side of the trackway, such frame consisting of the horizontal supporting members 20, the uprights 21, inclined braces 22, the diagonal brace 23, and the cap-piece 24.

This frame provides a fixed support for means which engage and move the projecting grip-controlling member carried by the car at such time and in such direction as to open the gripping jaws, and thereafter at the appropriate time to close the same. To this end the support has secured thereto a member which presents a stationary guideway for the roll 18, such member herein comprising a plate of L-shaped cross-section and presenting a wall 30 which has a suitably-shaped, depressed, curved portion at the end presented to the approaching car to engage the roll 18 and lift the same as the car passes the stationary support.

The end of the plate 30 which is presented to the approaching roller, acts in conjunction with a coöperating and similar plate 31 to provide a flared entrance mouth into which the roller enters, the walls of such mouth converging to form a curved guideway which confines the roller to a fixed path of travel, and is preferably designed to give the grip-releasing mechanism the most effective accelerated movement. While this guideway lifts the roller and thereby releasing the grip as the car proceeds, it thus confines the roller to a predetermined path, so that when it engages the lower plate it can move neither faster nor more slowly than prearranged, thus preventing too sudden a release as might occur through the rebound of the roller from the guide plate 30 under the momentum of the car.

The roller as it moves up the curved portion of the plate 30, turns the rock shaft and opens the grip, and as it reaches the elevated horizontal portion of the plate, travels along the same maintaining the grip released until it reaches the opposite and downwardly curved portion of the plate.

At that point positive means are provided for again depressing the roller to enforce a closing movement of the grip, such means being in the form of a similar L-shaped plate 32 presenting a curved wall which overlies the roller in its advance and forces it down from the dotted-line position shown in Fig. 4 to the full-line position therein indicated. Such curved plate is also preferably designed to give the roller the most effective accelerated closing movement. This depression of the roller turns the rock shaft 15 in the opposite direction and enforces the closing movement of the jaws about the cable strand 4'. 70 75 80

While the closing of the jaws is thus enforced by an extraneous member with which the roller 18 is brought into contact, such member is here arranged to exert a yielding pressure against the roller so that where some abnormal condition is present and the gripping engagement of the jaws with the cable is interfered with, no harm can result. Thus, for example, if the cable sticks in entering the recessed portions of the jaws, or if the presence of a cable splice interferes with the free entrance of the cable between the jaws, or some other abnormal condition is present which might result in damage if the closing of the cable grip were unyieldingly enforced, the illustrative form of apparatus is arranged to yield when a normally sufficient closing pressure has been applied. 90 95 100

For this purpose the depressing or grip-closing member of the stationary device is mounted upon a lever arm 33 pivoted at 34 upon the cap-piece 24, so that it is capable of an upward movement (see Fig. 5) being normally depressed, however, to its lowermost position (the limit of which is shown in Fig. 4) by any suitable means, such as the series of weights 35 (Fig. 1) depending from the end of the curved plate 32 by the rod 36. The plate 32 is guided in its lifting movement by the arc-shaped member 37 secured to the end of the plate 30 and engaged by guide members 38 carried by the plate 32. 110 115 120

When the car has advanced to a point which brings the roller into engagement with the plate 32, the roller will ordinarily be forced to follow the path provided by the upper plate 32 and the lower plate 30, and depressed to its lowermost position throwing the toggle past its center to close the jaws, in which position they are maintained by the toggle, the upper movable weighted plate 32 undergoing only such slight movement as is incidental to the increasing force required to close the toggle 125 as the latter moves past its center. If some obstruction or abnormal resistance is met with, however, so that the pressure of the weighted plate 32 is insufficient to move the toggle, the continued movement of the 130

car will carry the roller along a path which may approach the horizontal more or less as indicated in Fig. 5, causing the plate 32, the lever arm 33 and the weights 35 to lift toward some such position as is therein shown, thereby avoiding breakage which might result if an unyielding force were applied to depress the roller.

Herein means are also provided to indicate the presence of an abnormal condition, such as the refusal of the grip to close. For this purpose any suitable means may be provided, but herein for illustrative purposes I have shown an electric switch 40 controlled by the lifting of the movable lever 33 and acting through electrical connections to control some suitable indicating or similar device. While such switch might be connected to a device having the sole function of indicating the fault, herein I have diagrammatically represented the switch as controlling the motor circuit 41 which feeds the motor 42 for driving the cable 4, such motor being fed from the power circuit 43. The switch is normally closed by the spring 44, but, on the failure of the grip to close, the lever 33 lifts and the angle plate 45 carried thereby engages the end of the plunger 46, thereby opening the switch, cutting off the power from the driving motor and stopping the operation of the cable and indicating to the attendants the fact that the described fault is present.

35 In the normal operation of the apparatus as heretofore stated, there will be a slight but perceptible lifting movement of the weighted plate or lever 32. If the adjustment of the grip, however, is so slack or loose that it is not adapted to secure a firm grip upon the cable, such slight lifting movement will be absent. If the grip is adjusted to exert the required pull on the cable, there will be enough resistance in closing the toggle to give the slight perceptible lifting movement heretofore referred to. This slight movement, therefore, affords an indication of the normal working condition of the grip. Its absence indicates an abnormally small resistance, such as might arise from a slack grip or failure of the grip to engage the cable, while an abnormal lifting movement of the lever indicates the presence of an abnormal resistance as hereinbefore described.

It will be seen that the illustrative form of the invention avoids the necessity of carrying abnormally great weights on the car itself to close the grip, and provides all the necessary grip-closing force through means extraneous to the car, while at the same time this force may be applied yieldably to take care of any abnormal resistance. The grip-closing force may also be varied by varying

the weights 35 so as to adapt the force to varying conditions.

While I have shown and described for purposes of illustration one specific form of the invention, it is to be understood that the same is not limited to the particular application herein described, nor to the details or relative form or arrangement of parts, but that extensive deviations may be made therefrom without departing from the spirit of the invention.

75

Claims.

1. In a cable railway, the combination with a track, of a car-propelling cable, a car on the track, a grip on the car, a grip controller carried by the car, means located near the trackway to move said controller to release the cable and hold the grip open while the car travels a predetermined distance, and means also located near the trackway and in the path of said controller to enforce a grip-closing movement when the car has traveled said distance.

2. In a cable railway, the combination with a car, of a cable grip thereon, a grip controller carried by the car, and means automatically to open the grip and again close the same after the car has traveled a predetermined distance, said means comprising a fixed guideway formed by members between which said controller is adapted to enter in the progress of the car and impart thereto a definite, prescribed grip-opening movement, and other members between which said controller subsequently passes imparting thereto a definite, prescribed grip-closing movement.

3. In a cable railway, the combination with a track, of a car-propelling cable, a car on the track, a grip on the car, a grip controller, and means for automatically releasing the grip, comprising guiding members located near the trackway within the path of said controller and forming a guideway to actuate said controller and confine the same to a definite grip-opening movement.

4. In a cable railway, the combination with a track, of a car-propelling cable, a car on the track, a grip on the car, a grip controller, and means for automatically releasing the grip, comprising guiding members located near the trackway within the path of said controller and forming a guideway to actuate said controller and confine the same to a definite grip-opening movement, and means automatically and subsequently to close said grip.

5. In a cable railway, the combination with a track, of a car-propelling cable, a car on the track, a grip on the car, a grip controller, and means located near the trackway to engage said grip controller during the progress of the car and actuate the same

and confine it to a definite grip-opening movement.

6. In a cable railway, the combination with a track, of a car-propelling cable, a car 5 on the track, a grip on the car, a grip-controlling member, means automatically to impart a grip-opening movement to said member, and means located near the trackway subsequently to guide said grip-controlling member and impart thereto a grip-closing movement confined in a definite, 10 prescribed path.

7. In a cable railway, the combination with a car, of a cable grip thereon, grip-controlling means on the car including a linkage adapted to effect a positive closing of the grip, and means located within the path of said controlling member to apply a yielding grip-closing force thereto.

20 8. In a cable railway, the combination with a car, of a cable grip, a grip controller, means for automatically moving said controller to open said grip at a predetermined point, and means subsequently to close said 25 grip, said grip-closing means comprising a controller-engaging member located at the side of the trackway outside the limits thereof in the path of said controller and adapted to enforce a grip-closing movement 30 through engagement of the controller therewith.

9. In a cable railway, the combination with a car, of a cable grip, a grip controller, means for automatically moving said controller to open said grip at a predetermined point, and means subsequently to close said grip, said grip-closing means comprising a member arranged in the path of said grip controller and adapted to move 35 the same to enforce a grip-closing movement, said member being yieldably mounted to yield under an abnormal resistance by 40 said grip controller.

10. In a cable railway, the combination with a car, of a cable grip, a grip controller, 45 means for automatically moving said controller to open said grip at a predetermined point, and means subsequently to close said grip, said grip-closing means comprising a 50 pivoted member normally forced into a position to engage said grip controller and move the same to a grip-controlling position while adapted to yield under an abnormal resistance by said grip controller.

55 11. In a cable railway, the combination with a car, of an automatic cable grip-closing device, comprising a grip controller carried by the car, and a yieldable grip-closing member located near the trackway in 60 the path of said controller and adapted to move the same from a grip-released to a grip-closing position, said member being yieldable under an abnormal resistance.

12. In a cable railway, the combination 65 with a car, of an automatic cable grip-clos-

ing device, comprising a grip controller carried by the car, and a pivoted, weighted lever presenting a member lying in the path of the grip controller and adapted to move the same from a position of release 70 to a grip-closing position.

13. In a cable railway, the combination with a car, of a cable grip, a grip-actuating member on the car having a vertical grip-closing movement and means extraneous to 75 the car and located near the trackway for applying a yieldable grip-closing force to the grip actuating member at a predetermined point in the travel of the car.

14. In a cable railway system, the combination with a car, of a cable grip, a grip controller projecting from the car, and adapted when elevated to release the grip and when depressed to close the same, and an automatic controlling device located 80 near the trackway comprising a stationary support, curved guiding members between which said controller is adapted to pass as the car approaches said support and by which is adapted to be elevated to release 90 the grip, said support also presenting guide members adapted to maintain said controller elevated for an interval and presenting also curved and depressed guide members between which said controller passes 95 and by which it is adapted to be depressed to close the grip, the upper one of said depressed guide members being vertically yieldable under an abnormal resistance by 100 said controller to permit the passage of said car without depressing said controlling member.

15. In a cable railway, the combination with a car, of a cable grip thereupon, means acting to close said grip when the car 105 reaches a predetermined position, and electrically responsive means to indicate the failure of said grip-closing means to act.

16. In a cable railway, the combination with a car, of a cable grip carried thereby, 110 means adjacent the trackway to automatically close said grip when said car reaches a predetermined position, and means to cause stoppage of the cable-driving mechanism when the grip-closing means fails to act. 115

17. In a cable railway system, the combination with a car, of a cable grip thereupon, means adjacent the trackway to close the grip in a predetermined position of the car, said means being yieldable under an abnormal resistance by the grip-closing mechanism, and electrical means to indicate the failure of said grip to close. 120

18. In a cable railway system, the combination with a car, of a cable grip, automatic means for controlling the opening and closing of the grip, and means to indicate the failure of said grip-controlling mechanism to act. 125

19. In a cable railway system, the com- 130

- bination with a car, of a cable grip, a grip controller, a member adjacent the trackway lying within the path of the controller and adapted to move the same to close the grip
- 5 when the car reaches a predetermined position, said member being yieldable under an abnormal resistance by the grip-closing mechanism, a switch adapted to be moved under the yielding movement of said member, a motor for driving the cable, and a circuit controlling said motor controlled by said switch.
- 10 In a cable railway the combination with a cable of driving mechanism therefor,
- 15 a car, a cable grip carried by said car, a controlling member also carried thereby, means adjacent the railway to engage said member in the travel of the car and move the same into cable gripping relation and devices to stop the cable driving mechanism when the controlling member fails to move under engagement with said means.
- 20 In a cable railway the combination with a cable of driving mechanism therefor,
- 25 a car, a cable grip and controlling member
- therefor carried by said car, means adjacent the railway including a movable member adapted to engage said controlling member in the travel of the car and move the same into cable gripping relation and devices adapted to control the cable driving mechanism when said movable member is moved by engagement with said controlling member. 30
22. In a cable railway, the combination with a cable of driving mechanism therefor, a car, a cable grip and controlling member therefor carried by said car, means adjacent the railway including a movable member adapted to engage said controlling member 40 in the travel of the car and move the same into cable gripping relation, said member having a slight movement when the gripping member functions and relatively great movement when the gripping member fails 45 to function.

In testimony whereof, I have signed my name to this specification.

ALMON E. NORRIS.
